PERMUTATION LOCK

Charles H. Schamp, Milwaukee, and Daniel J. Foote, West Allis, Wis., assignors to Master Lock Company, Milwaukee, Wis., a corporation of Wisconsin

Application July 15, 1937, Serial No. 153,692

10 Claims. (Cl. 70—25)

The invention relates to locks and more particularly to permutation locks.

An object of the invention is to provide a permutation lock having improved and simplified means for placing the lock in locking condition upon the movement of the lockable member thereof, so as to avoid the possibility of inadvertently leaving the mechanism in releasable condition when the lockable member is returned to its locking position.

Another object of the invention is to provide a permutation lock which is reliable in operation, and which can be inexpensively manufactured and readily assembled.

15 The invention further consists in the several features hereinafter described and claimed.

An embodiment of the invention is shown in the accompanying drawing, wherein

Fig. 1 is a rear view of a permutation padlock constructed in accordance with the invention, parts being removed and broken away and parts being shown in section, the permutation mechanism having been adjusted to a position which will permit release of the shackle;

20 Fig. 2 is a sectional view of the padlock, taken generally along the line 2—2 of Fig. 1;

Fig. 3 is a sectional view taken generally along the line 3—3 of Fig. 1;

25 Fig. 4 is a view generally similar to Fig. 1 but showing the shackle on its opening movement;

Fig. 5 is a view similar to Fig. 4 but showing the shackle fully withdrawn;

30 Fig. 6 is a view similar to Fig. 5 but showing the shackle returned to its closed and locked position;

Fig. 7 is a perspective view of a control member of the mechanism;

Fig. 8 is a perspective view of an actuating member for the control member, and

35 Fig. 9 is a perspective view of a latch plunger.

In the drawing, 15 designates a lock case of any suitable shape, and in the present instance of cylindrical form and comprising a front plate

16 and an embossed rear plate 17, the former plate being integral with the cylindrical portion of the case. The case 15 has an enclosing cup-shaped shell 18, preferably a sheet metal stamping, which fits closely on the case and has a front cover plate 19 engaging the front plate 16

40 of the case. An embossed rear cover plate 20 marginally bears on the rear plate 17, and both of these plates are secured in place by a flange 21 formed by spinning over the rear edge of the shell 18. Preferably, the front and rear plates

45 16 and 17 are further secured in place by riveted

pins or posts 22 and 23, which also secure the front cover plate 19 of the shell to the front plate 16 of the case.

A guide member 25, preferably in the form of a sheet metal stamping, is rigidly secured within 5 the case, and comprises a flat portion 26 which rests on the inner face of the front plate 16 and is secured thereto by the riveted pin 23. Struck up from an end of the flat portion 26 of the member 25 is a flange 27 which extends between the 10 front and rear plates 16 and 17 and is provided with opposite lugs 28 which fit in anchor slots 29 formed in these plates. A round shackle-guiding opening 30 is formed in the flange 27.

A U-shaped shackle 31 has its legs slidably 15 passing through openings 32 formed in the case and shell. The longer leg of the shackle also

slidably and rotatably passes through the opening 30 in the guide member 25, and the shorter leg has a beveled end 33 and a locking notch 34 20 near this end. When the shackle is withdrawn to its outermost position, the shorter leg clears the shell 18, as seen in Fig. 5, and the shackle is then capable of being swung about its longer leg. The longer leg of the shackle is provided 25

with a keyway 35 in which slidably fits a guide tongue 36 struck up from the guide member 25. An annular groove 38 is formed about the end portion of the long shackle leg and slidably receives 30 therein a forked guide and stop plate 39

having an angularly extending finger 40 at one side, as best seen in Figs. 1, 3 and 8. The forked plate is confined on the shackle leg by the slidable engagement of an edge of the plate with the flat inner face of the case plate 17, which engage-

ment also guides the shackle leg and prevents rotation of the forked plate with respect to the case. The forked plate is engageable with the flange 27 of the guide member 25 to limit the 35 outward movement of the shackle, as seen in Fig. 40

5. When the shackle is in its outer or withdrawn position, it clears the tongue 36 to permit free swinging of the shackle.

A locking lever 41, forming a locking member, is pivotally mounted on the pin 22 and movably 45 carries a spring-pressed latch member, here shown to be in the form of a cylindrical latch plunger 42 slidable in a bore 43 formed in the locking lever at right-angles to the pin 22. The latch plunger has a beveled nose 44 engageable 50 in the shackle notch 34 to resist withdrawal of the shackle when the locking member is locked, as hereinafter described. A compressed coiled spring 45 within the locking lever extends within the hollow inner end of the latch plunger and 55

urges the latch plunger outwardly. A flat-bottomed slot or recess 46 in one side of the latch plunger receives the pin 22 which thus forms a stop limiting the outward movement of the latch plunger and also prevents relative rotation of the plunger with respect to the locking lever. An arcuate tongue or lip 47 on the locking lever cooperates with tumbler means hereinafter described.

10 A stud 48 is rigidly secured, as by riveting, to an embossed portion of the rear case plate 17 and projects forwardly through apertured portions of the front plate 16 and front cover plate 19. The tapered front end of the stud 48 loosely 15 fits in a bore 49 formed in an operating knob 50 which is rotatably mounted in the front plate 16. A dished dial plate 51 is carried on the knob against relative rotation, the knob having at its inner end a cross slot 53 forming a keyway. The 20 rim of the dial plate is surrounded by an annular bead 54, Fig. 2, which is embossed on the front cover plate 19 of the padlock shell. The dial plate bears the usual indicia, not shown, and conceals the riveted front ends of the pins 22 and 23.

25 An index notch 54', Fig. 2, is formed in the bead 54 to co-operate with the dial indicia.

A driving tumbler or disk 55 is concentric and rigid with the knob 50, as by keying and riveting it on the transversely slotted inner end of the 30 knob, and carries the usual transfer pin or lug 56. One or more additional tumblers or disks, two being shown in the present instance, are rotatable on the stud 48, and are designated by 57 and 58. These are generally similar except for 35 the positions of their transfer lugs 60. The tumblers are separated by washers 61 which have key projections entering a keyway 62 in the stud 48 and are placed under friction by a compressed coiled spring 63 surrounding the rear portion of 40 the stud 48. As seen in Fig. 2, the keyway 62 stops short of the front end of the stud so as to retain the tumblers and other parts on the stud prior to the attachment to the case of the rear plate 17, this plate and the several 45 parts mounted thereon thus forming an easily handled subassembly.

The tumblers 55, 57 and 58 have peripheral slots or notches 64 formed therein to admit the tongue 47 of the locking lever when these slots 50 are properly positioned and registered, as herein-after described, thus permitting the locking lever to be swung, as seen in Fig. 4, to allow the release or outward movement of the shackle 31.

Means are provided for automatically placing 55 the padlock in locking condition upon the movement of the shackle, and includes a shiftably mounted control member 65 which acts on the locking lever 41. The control member is preferably pivotally mounted and is here shown to 60 be pivotally carried on the stud 48 between the tumbler 58 and the coil spring 63. The control member is angularly shiftable by the tumbler 58 and has a releasable driving connection therewith which is preferably of the slipping or friction type and in the nature of a slipping clutch. The control member is here shown in the form 65 of a flat metal arm held in frictional clutching engagement with the adjacent flat face of the tumbler 58 by the coiled spring 63, the arm having an opening 66, Fig. 7, to receive the stud 48. The angular movement of the control member or arm is limited, as by providing an extension 67 thereon to engage the locking lever 41 and the post 23 at opposite ends of the angular travel of 70 the arm. The other end of the control arm has

an arcuate edge 68 concentric with the pivotal axis of the arm and of substantially the same radius as that of the tumblers, the ends of the arcuate edge being rounded. A lug 69 is bent out from the control arm adjacent the arcuate 5 edge, and its outer face is preferably offset inwardly from the arcuate edge so as to form a shallow depression or notch 70. The lug 69 lies in the path of outward travel of the finger 40 of the forked plate 39 on the long shackle leg, so 10 as to cause the control arm to move the tongue 47 of the locking lever 41 out of the tumbler notches and to prevent the return of the tongue into these notches, as hereinafter more fully described.

When the padlock is to be opened, the permutation knob 50 is turned alternately in opposite directions to successive predetermined positions, thus rotating the tumblers to bring the notches thereof into registered relation, as seen in Fig. 1, 20 for admitting the tongue 47 of the locking lever 41. The tumbler 58 is adjusted first and is turned in a counter-clockwise direction, as viewed in Fig. 1, causing the control arm 65 to turn counter-clockwise to the position seen in Fig. 1, by reason 25 of its frictional driving engagement with the tumbler, the control arm being stopped in this position by the engagement of the projection 67 with the locking lever. In this position the control arm will not obstruct the movement of the 30 locking lever 41. The shackle is then displaced outwardly with respect to the lock case, the notched short leg of the shackle turning the locking lever 41 to the position seen in Fig. 4, in which the locking lever tongue enters the tumbler 35 notches. The shackle is then freed from the latch plunger 42 and can be withdrawn to the outermost position seen in Fig. 5. During the outward movement of the shackle, the finger 40 on the long shackle leg engages the lug 69 on 40 the control arm 65 and swings this arm, in a clockwise direction as viewed in Fig. 4, a longitudinal edge of the control arm acting camwise and forcing the tongue 47 of the locking lever 41 out of the tumbler notches, thereby restoring the 45 locking lever to its normal locking position, as seen in Fig. 5. The lug 69 of the control arm is brought below the tongue 47, thus preventing this tongue from reentering the tumbler notches, which latter remain in their registered position. 50 When the control arm 65 is swung by the finger 40, the tumbler 58 does not move with it because of the presence of the tongue 47 in the tumbler notches and because of the frictional engagement of the tumbler with the adjacent spacing washer 61. The shackle-impelled control arm, being in 55 frictional driving engagement with the tumbler 58, has a tendency to cause movement of this tumbler out of unblocking position after the tongue 47 leaves the tumbler notches, but whether 60 or not such tumbler movement will occur is dependent on the degree of frictional engagement between the tumbler and the control arm and the speed of the control arm during the withdrawal of the shackle. The outward movement 65 of the shackle is limited by the engagement of the forked plate 39 on the shackle with the flange 27 of the guide member 25. In its outermost position the long leg of the shackle clears the guide tongue 36 of the guide member 25, 70 thereby permitting the shackle to be swung in either direction about its long leg. When the shackle is thus angularly displaced in either direction, it can not be moved longitudinally, since the guide tongue 36 is out of register with the 75

keyway 35 in the shackle, thus facilitating the manipulation of the device.

When the padlock is to be locked, the short leg of the shackle is re-entered into the case, the beveled end of the shackle leg forcing the latch plunger 42 into the locking lever 41, against the action of the spring 45, and the shackle reaching the locked position seen in Fig. 5. In this manipulation the finger 40 on the long shackle leg moves downwardly away from the lug 69 of the control arm 65, but the control arm remains in a position obstructing the unlocking movement of the locking lever 41, as seen in Fig. 6. The locking lever has a flat surface 71, Fig. 1, which is engageable with the peripheries of the tumblers to prevent rotation of the locking lever when the shackle on its inward movement is forced against the latch plunger. When the shackle reaches its innermost position, the latch plunger snaps into the shackle notch 34. The inward movement of the shackle is limited in any suitable manner, as by the engagement of the forked plate 39 with the curved inner wall of the lock case.

When the padlock is in locked condition, the end of the tongue 47 of the locking lever 41 tends to remain in the shallow notch or recess 70 in the end of the control arm 65, thus preventing jarring or shaking of the arm out of its obstructing position. However, the control arm may move through a considerable angle and still remain in obstructing position. If at any time the tumbler 58 should be turned in a clockwise direction, as viewed in Fig. 6, the control arm 65 would also turn in the same direction, but only through a partial revolution since the arm projection 67 would engage the stop-forming post 23. In its stopped position, the arm would still obstruct the movement of the locking lever 41.

In the locked position of the padlock, the tumbler notches remain in register with the tongue 47 of the locking lever 41, unless the knob 50 should be turned, but since the control arm 65 obstructs the movement of the locking lever, the lock can not be reopened except by working the permutation.

What we claim as new and desire to secure by Letters Patent is:

1. A permutation lock comprising a lockable member, locking means for said member including a movable locking member, a rotatably adjustable tumbler for blocking the unlocking movement of said locking member and movable out of blocking position, a shiftably mounted member for obstructing the unlocking movement of said locking member, said shiftably mounted member having a driving connection with said tumbler and movable thereby out of obstructing position when said tumbler is adjusted to its unblocking position, and means controlled by the movement of said lockable member for returning said shiftably mounted member to its obstructing position.

2. A permutation lock comprising a lockable member, locking means for said member including a movable locking member, a rotatably adjustable tumbler for blocking the unlocking movement of said locking member and movable out of blocking position, a pivotally mounted member for obstructing the unlocking movement of said locking member, said pivotally mounted member having a driving connection with said tumbler and movable thereby out of obstructing position, means for limiting the angular movement of said pivotally mounted member, and means controlled by the movement of said lockable member for returning said pivotally mounted member to its obstructing position.

able member for returning said pivotally mounted member to its obstructing position.

3. A permutation lock comprising a lockable member, locking means for said member including a movable locking member, a rotatably adjustable tumbler for blocking the unlocking movement of said locking member and movable out of blocking position, a shiftably mounted member for obstructing the unlocking movement of said locking member, said shiftably mounted member having a slipping, frictional driving connection with said tumbler and movable thereby out of obstructing position when said tumbler is adjusted to its unblocking position, and means controlled by the movement of said lockable member for returning said shiftably mounted member to its obstructing position.

4. A permutation lock comprising a lockable member, locking means for said member including a movable locking member, a rotatably adjustable tumbler for blocking the unlocking movement of said locking member and movable out of blocking position, a pivotally mounted member for obstructing the unlocking movement of said locking member, said pivotally mounted member having a slipping, frictional driving connection with said tumbler and movable thereby out of obstructing position, means for limiting the angular movement of said pivotally mounted member, and means controlled by the movement of said lockable member for returning said pivotally mounted member to its obstructing position.

5. A permutation lock comprising a lockable member, locking means for said member including a movable locking member, a rotatably adjustable tumbler for blocking the unlocking movement of said locking member and movable out of blocking position, a pivotally mounted member coaxial with said tumbler for obstructing the unlocking movement of said locking member, said pivotally mounted member having a slipping, frictional driving connection with said tumbler and movable thereby out of obstructing position, means for limiting the angular movement of said pivotally mounted member including a part on said pivotally mounted member projecting beyond the periphery of the tumbler, and means controlled by the movement of said lockable member for returning said pivotally mounted member to its obstructing position.

6. A permutation lock comprising a lockable member, locking means for said member including a movable locking member, a rotatably adjustable tumbler for blocking the unlocking movement of said locking member and movable out of blocking position, a shiftably mounted member for obstructing the unlocking movement of said locking member, spring means for holding said shiftably mounted member in slipping, frictional driving engagement with said tumbler for movement of said shiftably mounted member out of obstructing position, and means controlled by the movement of said lockable member for returning said shiftably mounted member to its obstructing position.

7. In a permutation padlock, the combination of a shackle, shackle-locking means including a rotatably adjustable tumbler and a shiftably mounted member both movable to release said shackle, said shiftably mounted member having a frictional driving connection with said tumbler and movable thereby to shackle-releasing position when said tumbler is adjusted to shackle-releasing position, and means controlled by the

movement of the shackle for returning said shiftably mounted member to locking position.

8. A permutation lock comprising a lockable member, locking means for said member including a movable locking member having a projection, a rotatably adjustable tumbler for blocking the unlocking movement of said locking member and movable out of blocking position, said tumbler having a peripheral notch to receive said projection in the unblocking position of said tumbler, a pivotally mounted arm coaxial with said tumbler for obstructing the unlocking movement of said locking member, said arm having a frictional driving connection with said tumbler and movable thereby out of obstructing position, said arm having a laterally projecting lug and having a shallow notch at the attached end of said lug to receive the projection of the locking member when said arm is in obstructing position, and means controlled by said lockable member on its unlocking movement engageable with said lug to swing said arm to its obstructing position.

9. A permutation lock comprising a lockable member, locking means for said member including a movable locking member, a rotatably adjustable tumbler for blocking the unlocking move-

ment of said locking member, and a shiftably mounted control member having a slipping clutch connection with said tumbler to displace said control member when said tumbler is adjusted to unblocking position, said lockable member on its movement having an impelling connection with said control member to effect reblocking of said locking member.

10. A permutation lock comprising a lockable member, locking means for said member including a movable locking member, a rotatably adjustable tumbler for blocking the unlocking movement of said locking member, and a pivotally mounted control member coaxial with said tumbler and having a slipping clutch connection with said tumbler for effecting movement of said control member in one direction when said tumbler is adjusted to unblocking position, means for limiting the angular movement of said control member, and means controlled by the movement of said lockable member for moving said control member in the opposite direction to effect reblocking of said locking member.
